Primary Examiner—Louis S. Zarfas
Attorney, Agent, or Firm—Volpe and Koenig**[57]****CLAIM**

The ornamental design for a tile edging strip, as shown and described.

DESCRIPTIONFIG. 1 is a perspective view from one end of the tile edging strip which is broken in the center to indicate indeterminate length, and the pattern of the openings is repeated throughout the length thereof; and,
FIG. 2 is an enlarged view of the other end.**1 Claim, 1 Drawing Sheet**
